FENDER FOR AN AUTOMOBILE

Homer C. La Gassey, Jr., Royal Oak, Mich., assignor
to Chrysler Corporation, Highland Park, Mich., a
corporation of Delaware

Application August 13, 1959, Serial No. 57,168

Term of patent 7 years

(Cl. D14—6)

Fig. 1 is a side elevational view of a fender for an automobile showing my new design;

Fig. 2 is a top plan view thereof;

Fig. 3 is a front elevational view thereof;

Figs. 4, 5 and 6 are sectional views taken on the lines 4—4, 5—5 and 6—6 of Fig. 1; and

Figs. 7 and 8 are sectional views taken on the lines 7—7 and 8—8 of Fig. 3.

The essential features of my design reside in those portions shown in full lines.

I claim:

The ornamental design for a fender for an automobile, substantially as shown and described.
